United States Patent Office.

WILLIAM S. COLWELL, OF PITTSBURG, PENNSYLVANIA.

Letters Patent No. 73,504, dated January 21, 1868.

IMPROVEMENT IN PLOUGHS.

The Schedule referred to in these Letters Patent, and making part of the same.

TO ALL WHOM IT MAY CONCERN:

Be it known that I, WILLIAM S. COLWELL, of Pittsburg, in the county of Allegheny, and State of Pennsylvania, have invented a new and useful Improvement in Ploughs; and I do hereby declare that the following is a full and exact description thereof, reference being had to the accompanying drawings, and to the letters of reference marked thereon.

The nature of my invention consists in providing a plough with a mould-board, the longitudinal and transverse surfaces of which are convexed in the manner and for the purpose hereinafter described.

To enable others skilled in the art to make and use my invention, I will proceed to describe its construction and operation. In the accompanying drawings, which form part of my specification—

Figure 1 is a top view of a plough, provided with my improvement in mould-boards.

Figure 2 is a side view of the same.

Figure 3 is a transverse section of the plough when cut through at line y of fig. 2.

Figure 4 is a longitudinal section of the plough when cut through at line z of fig. 2.

In the drawings, A represents the mould-board, B represents the plough-share, D represents the land-side, C represents the standard to which the plough-beam is attached. The share, land-side, and standard are constructed in any of the known forms, and of any desired size. The surface of the mould-board A is made convexed, by making the arc of the convexity extend from the point of the share B to the heel of the mould-board A, as indicated by the dotted lines, marked x' in figs. 1 and 2, and also making the mould-board convexed, with the arc of said convexity extending from the point marked O to the point marked O', as indicated by the line marked y in figs. 1 and 2. The arcs of the convexity of the mould-board A will be plainly seen by placing a "straight-edge" on the lines x' and y, and by placing the "straight-edge" on the lines x' and z of fig. 2, the surface of the mould-board should be straight or parallel with the longitudinal plane of the "straight-edge".

By providing ploughs with mould-boards, constructed as herein described, their draught will be steady, light, easy, and uniform, which are qualities very desirable in a plough.

I wish it clearly understood that I do not claim broadly a mould-board having a convexed surface, for such device is well known to the manufacturers of ploughs; but, having thus described the nature, construction, and operation of my improvement,

What I claim as of my invention, is—

A plough provided with a mould-board, having the surface convex, in the manner and for the purpose herein described and set forth:

W. S. COLWELL.
